UNITED STATES PATENT OFFICE.

JUSTUS C. GOOSMANN, OF PEORIA, ILLINOIS.

THERMOSTATIC SWITCH CONTROL.

Application filed March 3, 1921. Serial No. 449,487.

This invention relates in general to switch controls, and more particularly, to thermostatic controls, by which a switch is automatically thrown in and out at predetermined temperature variations. While this control is capable of use for a variety of purposes, it is especially adapted for use in connection with refrigerating apparatus for the purpose of starting the driving motor when the temperature in the refrigerating chamber reaches a predetermined maximum, and for stopping said motor and thereby the apparatus when the temperature in the chamber reaches a predetermined minimum.

One of the purposes of this invention is to provide a control of the character indicated, which will be accurate and reliable in operation, which is capable of adjustment to vary the range of temperatures at which the switch will be actuated, and also to vary the minimum temperature at which the switch will be actuated, and one which will be simple in construction, cheap to manufacture, and not liable to get out of order in operation.

Another feature of my invention resides in the novel structure employed for maintaining the thermostatic element, in the present instance an expansible member, in proper alignment so that there will be no binding or undue friction between moving parts which might detract from the reliability of the apparatus, and which will prevent the member from twisting and becoming distorted so as to interfere with its accuracy of operation.

Other advantageous features of my invention should be readily appreciated as the same becomes better understood by reference to the following description when considered in connection with the accompanying drawings.

Referring to the drawings:

Fig. 1 is a side elevation of a switch control embodying my invention;

Fig. 2 is a transverse sectional view taken on the line 2-2 of Fig. 1; and

Fig. 3 is a longitudinal sectional view looking toward the right at Fig. 1.

By reference to the drawings, it will be observed that my invention embodies a frame upon which the operating parts are mounted, comprising a base 5, an upright 6, a top portion 7, and an upwardly extending bracket 8 upon which the switch, design-

nated generally by reference character 9, is mounted. The supporting structure, however, may obviously be varied to meet various requirements, and in many instances, the whole or part of the mechanism carried by the frame will be enclosed within a suitable casing or housing as a matter of protection to the apparatus.

The switch 9 may be of any preferred construction, adapted to make and break an electric circuit, but in the present instance I have illustrated a common form of snap switch comprising a pair of terminals 11, arranged in spaced relation, one of which only is shown in Fig. 1, and a contact member 12 pivotally mounted at 13 upon a lever 14 fulcrumed in the switch casing at 10, this member being adapted to be swung from open position shown in Fig. 1 to closed position, wherein it contacts with the terminal 11. An expansion spring 15 serves to throw the switch to open or closed position when the lever 14 is swung on its fulcrum past a dead center line connecting the fulcrum 10 with the longitudinal axis of the contact member. Obviously, any other preferred type of snap switch might be employed.

The lever or switch arm 14 is actuated by a thermally responsive element, consisting in the present instance, of an expansible bellows 16 of well known construction, adapted to be filled with a suitable fluid readily expansible under the action of heat, this element being rigidly secured at one end to the base 5 of the frame by means of an extension 17 upon which a nut 18 is threaded. Since it is desirable in most instances, that the element be located remote from the chamber, the temperature of which is to be controlled, I employ an extension tube 19 connected at one end with the element, and at its other end with a thermostatic member 21 of tubular shape, and closed at its outer end. This member may, if preferred, be made of copper or other metal having a relatively high coefficient of expansion, in which instance, it is preferable to employ a fluid in the bellows and thermostatic member which is not readily expansible under the action of heat, the expansion and contraction of the tubular member 21 being relied upon to displace sufficient fluid to cause the desired actuation of the bellows.

Preferably, however, the member 21 is made of non-expansible material, and the bellows and this member are filled with a

fluid readily sensible to heat, such as liquefied sulphur dioxide, for instance, the expansion of this fluid under the action of heat being relied upon to elongate the bellows, 5 which automatically contracts, (as will be hereafter explained) as the pressure therein diminishes upon the contraction of the fluid.

Upon the unattached or free end 22 of the bellows, there is mounted a flange disc 23, 10 against which the lower end of an expansion spring 24 abuts. The upper end of this spring engages a similar, but oppositely disposed disc 25, and the normal tension of this spring may be regulated by an adjustable 15 sleeve 26, threaded through a tapped opening in the top 7 of the frame. By threading this sleeve 26 downwardly or upwardly, the tension on spring 24 is increased or diminished respectively, by which adjustment, the 20 opposition of spring 24 to the longitudinal expansion of the bellows may be regulated so that the temperature at which initial expansion of the bellows will take place may be controlled to a fine degree of nicety.

25 An operative connection between the bellows and the snap switch lever 14 is provided, this connection consisting of a rod 27 attached at its lower end to the bellows and a rod 28 attached at its upper end to the 30 switch lever 14 through the intermediary of a connecting element 29. A lost motion connection is provided between the rods 27 and 28, consisting in this instance, of slots 31 formed in a sleeve 32 at the lower end of rod 35 28 in which a pin 33 projecting at opposite sides of the telescopic end 34 of the rod 27 is adapted to work. For purposes of regulating the range of temperatures between the extremes of which the switch will be operated 40 by the bellows, I employ a coiled expansion spring 35 surrounding the telescopically connected portions of the connecting rods, the lower end of this spring being adapted to bear against a flanged collar 36 mounted 45 upon the rod 27 and its upper end against an adjustable nut 37, which is locked in adjusted position by a lock nut 38.

It will be obvious, as previously explained, 50 that the spring 24 determines the point at which the expansible element will begin to expand, and when expansion takes place, the rod 27 will be moved upwardly, the pin 33 sliding in the slots 31 until the tension produced on the spring 35 causes an upward 55 movement of the switch lever 14 sufficient to bring the switch spring 15 into action, whereupon the switch will be quickly thrown by the spring 15, thus snapping the outer end of the lever 14 quickly upwardly. The 60 reaction from the switch movement, however, will not be transmitted to the bellows through the rod 27 by reason of the lost motion connection between this rod and rod 28, and therefore, the bellows element is protected 65 against the jars and shocks to which it

would otherwise be subjected were the yieldable connection above described not provided. Upon reverse or contracting movement of the element, the rod 28 will be pulled downwardly by the pins 33, pulling 70 against the lower end of the slots 31, and when the switch is actually thrown by the spring 15, the quick downward movement of rod 28 will again be absorbed by the spring 75 and lost motion connection and will not be transmitted to rod 27 and the element.

Since the element is mounted at one end only on the frame, there is a tendency during its expansion and contraction movements to twist or become distorted or disposed out of proper alignment, with the result that these various working parts may be caused to bind so as to detract from the reliability of the apparatus. For the purpose of maintaining the element in the proper alignment 85 without imposing a friction which would retard its movements, I have provided a guiding construction as follows: At opposite sides of the element, the base 5 is equipped with upwardly projecting lugs 39, the outer vertical faces of which are horizontally grooved to accommodate the inturned ends 41 of a pair of vertically disposed yoke-shaped members 42. The central upwardly extending portions 43 of these yoke-shaped members are disposed in opposed relation at opposite sides of the free end 44 of the element. These portions are provided at their inner faces with horizontal grooves 45 and the cylindrical portion of the element is 90 likewise provided on opposite faces with horizontal grooves 46. Guiding elements 47, having their ends beveled to provide knife-edged bearings in the grooves 45 and 46 respectively, are interposed between the 95 members 42 and the free end of the element, and the parts are all held in operative position by a pair of tractile springs 48 connected at opposite ends to the yokes 42.

It will be obvious that the members 42 are 110 prevented from tilting laterally by reason of the spaced relation of the bearing lugs 39. Consequently, twisting or tilting movements of the free end of the element are prevented by the elongated bearing surfaces of the guiding elements 47. These elements, however, being pivotally related with the element and with the yoke members, do not interfere with the longitudinal expansion 115 and contraction of the element, nor do they impose any frictional resistance to its movements, with the result that the element is maintained in proper alignment, but its accuracy is not diminished by frictional resistance.

120 It is believed that the construction, operation, and many of the inherent advantages of this invention will be apparent from the foregoing without further description, and while I have shown and described a pre- 125

ferred embodiment of the invention, obviously, the details of construction may be varied within considerable limits without departing from the essence of the invention, as defined in the following claims.

I claim:

1. In a switch control, the combination of a snap switch, an expansible heat-actuated element, a connection between said element and said switch including an adjustable spring, and an adjustable spring tending to resist the expansion of said element.

2. In a switch control, the combination of a switch, an expansible heat-actuated element, a pair of rods connected with said switch and said element respectively, a lost motion connection between said rods, an adjustable spring normally urging said rods apart, a spring arranged to yieldingly resist the expansion of said element, and means for regulating the tension of said last-mentioned spring.

3. In a switch control, the combination of a switch, an expansible heat-actuated element, a connection between said element and said switch, means for yieldingly resisting the expansion of said element, and resilient means acting upon the movable end of said element for maintaining said element in predetermined alignment during the expansion and contraction thereof.

4. In a switch control, the combination of a switch, a thermostatic element, operative connections between said switch and said element, and yieldably mounted means engaged with the movable end of said element for maintaining the same in predetermined alignment.

5. In a switch control, the combination of a frame, a thermostatic element fixed at one end thereto, a switch, an operative connection between the free end of said element and said switch, a pair of members mounted on

said frame at opposite sides of said element, guiding members pivotally engaging said members respectively and the free end of said thermostatic element, and springs arranged to hold said members and elements in operative position.

6. In a switch control, the combination of a frame, a thermostatic element fixed at one end thereto, a switch, a connection between the free end of said element and said switch, a pair of members pivotally supported by said frame at opposite sides of said element, a guiding element disposed between each of said members and the free end of said thermostatic element, and springs for urging said members toward each other.

7. In a switch control, the combination of a frame, a thermostatic element attached thereto at one end, a pair of members pivotally supported on said frame at opposite sides of said element, guiding elements disposed between said members and the free end of said element and having elongated knife-edged bearings engaging said element and said members, and tractile springs connecting said members to retain said guiding elements in operative position.

8. In a switch control, the combination of a frame, a thermostatic element attached at one end thereto, a switch carried by said frame remote from said element, a yieldable connection between said element and said switch, a spring normally resisting the expansive movements of said element, means for regulating the tension of said spring, and means for maintaining said element in alignment, said last-mentioned means including a plurality of guiding elements pivotally engaged with said thermostatic element, and means for yieldingly retaining said guiding elements in position.

JUSTUS C. GOOSMANN.
